CLAIM

The ornamental design for an expandable digging bucket, as shown and described.

DESCRIPTION

FIG. 1 is a perspective view of an expandable digging bucket showing our new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a rear elevational view thereof;

FIG. 7 is a perspective view of a second embodiment;

FIG. 8 is a front elevational view of FIG. 7;

FIG. 9 is a right side elevational view of FIG. 7;

FIG. 10 is a left side elevational view of FIG. 7;

FIG. 11 is a top plan view of FIG. 7; and,

FIG. 12 is a bottom plan view of FIG. 7.

FIG. 8

FIG. 2.

FIG. 5.

FIG. 4.

FIG. 3.

FIG. 12.

FIG. 6.

FIG. 11.

FIG. 10.

FIG. 9.
